United States Patent Office.

J. H. BURNETT, OF WILLIAMSTOWN, NEW YORK.

Design No. 3,596, dated August 3, 1869.

DESIGN FOR A TRUNK-CLASP CASTER.

The Schedule referred to in these Letters Patent and making part of the same.

To all whom it may concern:

Be it known that I, J. H. BURNETT, of Williamstown, in the county of Oswego, and State of New York, have originated and designed a new Pattern for a Trunk-Clasp Caster, of which the following is a full, clear, and exact description, reference being had to the accompanying drawings, making part of this specification.

Figure 1, in the drawing—

A is the frame, constructed in the form as shown in the accompanying drawings; and

B is the flange raised around the roller D, for strengthening and bracing the frame, as shown in the drawing.

E is the pin that holds the roller in the flange on the outside of the frame, as shown in fig. 1.

Figure 2 is a trunk, showing the clasp-caster riveted to the bottom of the trunk, and each corner of the trunk, as shown in fig. 2 of the accompanying drawings.

What I claim as my invention, and desire to secure by Letters Patent, is—

The design or pattern for a trunk-clasp caster herein set forth.

J. H. BURNETT.
